UNITED STATES PATENT OFFICE.

WILLIAM A. LORENZ AND WILLIAM H. HONISS, OF HARTFORD, CONNECTICUT, ASSIGNORS TO FELIX W. LEINBACH AND CLARENCE A. WOLLE, BOTH OF BETHLEHEM, PENNSYLVANIA.

PAPER-BAG MACHINE.

SPECIFICATION forming part of Letters Patent No. 361,951, dated April 26, 1887.

Application filed October 18, 1886. Serial No. 216,504. (No model.)

To all whom it may concern:

Be it known that we, WILLIAM A. LORENZ and WILLIAM H. HONISS, of Hartford, Connecticut, have jointly invented a certain new and useful Paper-Bag Machine, of which the following description and claims constitute the specification, and which is illustrated by the accompanying fourteen sheets of drawings.

This machine automatically manufactures square-bottom paper bags from continuous tucked paper tubing.

Figures 1, 2, and 3 of the drawings show plan, side, and end views, respectively, of a portion of a tucked paper tube which is called by us a "blank." Fig. 4 is a side view of this blank pressed together near its center. Figs. 5 and 6 are side and plan views of the blank, showing one end opened up into a box-like form. Figs. 7 and 8 are side and plan views of the blank, showing the box-like form partially folded down into a shape which we term the "diamond." Figs. 9 and 10 show side and plan views of the same fully folded down and lines of paste applied to the diamond. Fig. 11 is a side view of the blank, the diamond being shaped to a curve, and the rear flap being partially folded over. Fig. 12 is a plan of the blank, showing the second flap fully folded over on the diamond. Fig. 13 is a plan view, showing the first flap folded over onto the second flap, thus completing the bag. Fig. 14 is a perspective view of the bag fully opened up. Fig. 15 is a side view of a portion of the machine which draws forward the tucked paper tubing and folds the blanks as far as the shape shown in Fig. 6. Fig. 16 is a plan thereof. Fig. 17 is a section on the line *a b* of Fig. 15, looking to the left. Fig. 18 is a section of a portion of Fig. 16, and is taken on the longitudinal center *c d* of the machine. Fig. 19 is an end view of the right-hand part of Figs. 15 and 16. Fig. 20 shows portions of Fig. 19, but in another position. Figs. 21 and 22 show plan views of the upper parts of Figs. 19 and 20, together with the blank at two different stages in the folding. Fig. 23 is a section of Fig. 15 on the line *e f*. Fig. 24 is a plan view of the remainder of the machine, which folds the bag-blank from Fig. 6 to completion. Fig.

25 is a section on line *m n* of Fig. 24. Fig. 26 is a section of Fig. 25 on the line *g h*. Fig. 27 is an end view of a portion of Fig. 25, looking to the left on the line *i j*. Fig. 28 is an enlarged section of Fig. 25 on the line *k l*, showing a portion of the machine and folded blank. Fig. 29 shows the same parts as in Fig. 28, but in a more advanced position. Figs. 30 and 31 are side views of a portion of Fig. 25, showing the operation of flap-folding. Figs. 32 and 33 represent a modification of the blank-folding portion of Figs. 15 and 19, and are side and end views, respectively. Fig. 34 is another modification of the same. Figs. 35 and 36 represent a modification of the flap-folding devices. Fig. 37 represents a side view of another modification of the same upon a reciprocating carriage. Figs. 38 and 39 represent side views in two positions of another modification of the same. Figs. 40 and 41 represent side and plan views of another modification of the same. Figs. 42 and 43 represent side views in two positions of another modification of the same. Figs. 44, 45, and 46 represent side views in two positions and an end view of another modification of the same. Fig. 47 is an enlarged view of a portion of Fig. 44. Figs. 48 and 49 are front and sectional plan views, respectively, of a modification of the sweeper apparatus, the latter being taken on the line *s t* of Fig. 48.

For greater clearness the following gears are not shown in full in side view, but have parts broken away or teeth omitted, namely: 21, 22, 25, 26, 28, 29, 32, 33, 67, 85, 86, 87, 88, 91, 93, 95, 184, 185, 186, 187, 193, 196, 222, 223, 247, 325, 326, 328, 332, 339, 340, 418, and 433.

The numeral 1 indicates a bag-blank severed from a continuously tucked paper tube, and having two inwardly-projecting tucks, 2 and 3, and two longitudinal slits, 4 and 5, a lip, 6, and a recess portion, 7, the tucks extending the entire length of the blank, and the slits extending only a short distance into one end thereof, as shown in Figs. 1 to 3. The form which we call the "box" is that shown in Figs. 5 and 6, and is marked with the numeral 8. The form which we call the "diamond" is that shown in Figs. 7 to 10, and is marked

with the numeral 9. The ends of the diamond are called "flaps" by us, that marked with the numeral 10 being called the "first flap," and that marked with the numeral 11 the 5 "second flap."

The numeral 12 indicates the place where one side of the diamond laps over the other side, in order to prevent paste from entering the bag and to make the bag smooth on the 10 inside of its bottom. Lines of paste 13 are placed on both sides of the lap 12, as shown in Fig. 10. The second flap, 11, is folded over on the middle rectangular portion of the diamond in Fig. 12, and the first flap, 10, is folded over upon the second flap, as shown in Fig. 15 13, and the bag is thus completed.

In this machine tucked paper tubing is drawn from a former and is delivered to and gripped upon a traveling folding-bed, and is 20 separated into blanks at each stroke of this bed. This bed, as we construct it, is a rocking one, and is provided with suitable folding apparatus for making the primary bottom folds upon the bag. From this folding-bed the partially-folded bag is delivered by suitable mechanism to gripping-rolls, which pass it to a second traveling folding-bed, upon which the pasting and flap-folding are accomplished. 25 This second bed is an endless one as we prefer to construct it, and is provided with clamping and folding apparatus, as herein set forth. The combinations of mechanism with these folding-beds form the most important parts of our present improvements, and they may be 30 greatly modified in form and arrangement, and very much in their details, without departing from our invention.

In the principal figures the first traveling folding-bed is represented as supported upon 40 a central cam-carrying pivot, as shown in Fig. 15.

The second traveling bed is shown as supported upon a central shaft, with which it revolves, as shown in Fig. 25, and this bed is 45 represented as carrying two pairs of retracting-fingers, being arranged to act in succession from the inside to the outside of the endless folding-bed. Beyond this bed are shown flap-folding blades and rolls for flattening folded 50 bags.

We will first describe that section of this paper-bag machine which draws the tucked paper tubing from the former and delivers it to the traveling folding-bed, together with the 55 mechanism for severing the tubes into bag-blanks.

In Figs. 15, 16, and 17, Sheets 2 to 4, the numeral 15 represents the driving-pulley by which power is communicated to this machine, and 16 is a loose pulley adjacent thereto. The pulley 15 is fastened to a shaft, 17, which has bearings in two uprights, 18 and 19, these latter being fixed to the bed 20 of the machine. A driving-gear, 21, is fixed to the 60 shaft 17 and meshes into a gear, 22, upon the shaft 23, upon which a hand-wheel, 24, is fixed. Upon the shaft 23 is fixed a gear, 25, meshing

into an intermediate gear, 26, turning upon a stud, 27. This gear 26 meshes into two gears, 28 and 29, which turn upon shafts 30 and 31, 70 respectively. The gears 28 and 29 mesh into gears 32 and 33, respectively, which turn upon shafts 34 and 35. To the gears 28 and 32 are secured the drawing-rolls 36 and 37, respectively, which also run upon the shafts 30 and 34, respectively. These rolls are narrower than the tucked tube, and are also reduced in diameter in the middle, forming two annular projections, which press upon the tube between its edges and the bottoms of the inwardly-projecting tucks, permitting these to preserve their roundness and elasticity. Pressure is exerted upon the upper drawing-roll, 37, through the cam-handles 42 and 43, by means of springs 44 in the caps 46 and 47, attached to the uprights 18 and 19. The cam-handles 42 and 43 extend into the caps 46 and 47 and into the uprights 18 and 19 and press upon arms 48 and 49, in which is supported the shaft 34, and which arms are pivoted, at 50, to the uprights 18 and 19. The cam-handles 42 and 43 may be swung away from over the arms 48 and 49, permitting the roll 37 to be swung back into the dotted position 52, so that the tube 57 may be "threaded" or drawn over the knife 58 with 80 ease. Pressing-rolls 53 and 54 are attached to the gears 29 and 33 and revolve upon the shafts 31 and 35, respectively. Pressure is exerted upon the upper shaft by means of springs 55 in the caps 46 and 47. 100

To the left of the drawing-rolls 36 and 37 is shown a portion of the former 56, with the tucked paper tube 57 upon it. The former 56 has projecting from the forward end thereof (within the tucked paper tubing 57) a former-knife, 58, which extends centrally between the rolls 36 and 37 and 53 and 54. This knife is T-shaped, being of the width of the tube between the pressing-rolls, and being narrow where it passes between the rolls 36 and 37. 110 A hole, 59, is made in said knife 58, to allow the rolls 53 and 54 to press the tube. The knife 58 extends beyond the rolls 53 and 54, and its front is suitably serrated, as shown, for instance, in Fig. 17. 115

Above the former-knife 58 and the tube which envelopes the same there is placed a lip-knife, 60, (fastened to the uprights 18 and 19,) whose serrated front edge is preferably curved at the sides, and should be placed a little to the rear of the front of the former-knife 58. In front of the two knives 58 and 60 is shown a striker, 61, which is revolved by means of a shaft, 62, running in a bracket, 63, fixed to the upright 19. The shaft 62 is 120 driven by means of a bevel-gear, 64, fixed thereto, which gear meshes into a bevel-gear, 65, upon the shaft 66. This shaft is driven by a gear, 67, meshing into the driving-gear 21. Upon the shaft 66 is secured an arm, 70, 125 carrying two slitting-knives, 71 and 72. The former 56 is provided with two slots, 73 and 74, to allow the slitting-knives to pass into it. 130

The mechanism for imparting an oscillating

motion to the traveling folding-bed will now be described, together with the preferred form of mechanism for driving the gripping or pressing plate upon this bed.

- 5 Upon the shaft 66 is fixed the crank-disk 76, carrying a crank-pin, 77, which holds one end of the connecting-rod 78, the other end of which rod is pivoted upon the stud 79, attached to a rocking or reciprocating carriage, 80. This forwardly and backwardly moving carriage vibrates upon the shaft 81 in brackets 82 and 83. Upon this shaft revolve two gears, 85 and 86, meshing into two gears, 87 and 88, fixed to the shaft 89 in the bracket 90. 15 Meshing into the gear 85 the gear 91 is shown upon the stud 92, the latter gear meshing into the intermediate gear, 93, upon the stud 94, this gear meshing into the gear 95 upon the shaft 23. 20 Upon the upper part of the carriage 80 there is a bag-blank-clamping apparatus, consisting of a presser-plate, 98, which will be seen by referring to Figs. 15, 16, 19 to 23, Sheets 2 to 6, and which has a vertical motion 25 to the dotted position shown in Fig. 18. This presser-plate is secured to two brackets, 100 and 101, which receive vertical motion by means of two presser-arms, 102 and 103, which are fixed to a rocking shaft, 104, which arms 30 carry pins 105 and 106, which enter the brackets 100 and 101. To the lower end of the bracket 100 a link, 107, is attached, pivoted at 108 to the carriage 80, which gives the presser-plate a parallel motion. To the shaft 35 104, at the outer end of the carriage 80, there is attached an arm, 109, to which is pivoted a connecting-rod, 110, connected at its other end to a swinging arm, 111, which arm rocks upon a stud, 112, fastened to the connecting-rod 78. 40 On the swinging arm 111 a stud, 113, is fixed, which holds the connecting-rod 110, and upon its inner end holds the roller 114, which runs in a cam-groove, 115, in the crank-disk 76, giving a vibrating motion to the arm 111 as 45 the crank-disk revolves, and, through the arm 111 and intermediate parts, imparts a vertical motion at suitable intervals to the presser-plate 98.

The various mechanisms attached to the traveling folding-bed, as we prefer to construct them, will now be described. They comprise a tuck-entering motion, a blade-folding motion for making the primary folds upon the bottom of the bag, together with a lifting-motion for holding a part of the bag-bottom.

Carriage 80 has two ears, 118 and 119, carrying fixed studs 120 and 121, upon which are placed the two rocking tuck-levers 122 and 123. These levers are provided with studs 124 and 125, carrying cam-rolls 126 and 127, which run in the cam-grooves 128 and 129 of cams 130 and 131, which cams are attached to the gears 85 and 86, running upon the shaft 81 at both sides of the carriage 80. To the upper ends of these tuck-levers 122 and 123 are secured tuck-blades 132 and 133, which have

triangular ends projecting inwardly toward the center of the machine, and these blades receive a reciprocating motion in and out from the carriage 80 as the cams 130 and 131 revolve. In the upper ends of the tuck-levers 122 and 123 are placed two shafts, 134 and 135, to which are secured box-blades 136 and 137, which also have triangular-shaped ends. These 75 blades 136 and 137 are operatively connected with a cam on shaft 81, and receive therefrom a rotary reciprocating motion of about one hundred and eighty degrees, as shown in Figs. 16 and 21, respectively. This movement is 80 attained by means of connecting devices, as follows: Pinions 138 and 139, fixed on the box-blade shafts 134 and 135, are driven by means of racks 140 and 141, which slide in casings attached to the upper ends of the tuck-levers. 85 Those racks are operated by means of connecting-rods 142 and 143, which are connected at the pivots 144 and 145 to oscillating levers 146 and 147. These oscillating levers swing upon the hubs of the tuck-levers 122 and 123, 90 which oscillate upon studs 120 and 121. (Seen best in section in Fig. 23, Sheet 6.) The opposite ends of the oscillating levers 146 and 147 are bevel-sectors, which mesh into bevel-sector arms 148 and 149, fastened to the shaft 95 150, which oscillates in ears in the carriage 80. To the outer end of the shaft 150 is secured the arm 151, carrying a pin, 152, upon which a roller, 153, revolves, engaging in a cam-groove, 154, in the cam 155, which cam is fixed 100 to the other cam, 130, and revolves with it, thus transmitting an oscillating motion simultaneously to the arms 146 and 147 and through them giving the oscillating motion to the box-blades 136 and 137. The tuck-levers 122 and 105 123 and the levers 146 and 147 are all held upon the studs 120 and 121 by means of collars 156 and 157.

The tuck-levers 122 and 123 receive the proper oscillating motion from the cams 130 110 and 131 at suitable intervals, thus driving the blades attached to their upper ends to and from the carriage. The levers 146 and 147 also receive a proper oscillating motion from the cam 155 at suitable intervals, transmitting an oscillating motion to the box-blades 136 and 137, all of which motions occur during the rocking motion of the carriage 80.

From the front of carriage 80 two ears, 160 and 161, project, between which a sector, 162, 120 is pivoted upon a stud, 163. To the upper end of the sector 162 there is attached a lifter-plate, 164, which is curved at its forward end and which receives oscillating motion by means of the sector 162, meshing with and 125 driven by the sector 165. This latter sector is fastened to a shaft, 166, swinging in a projecting bracket, 167, on the carriage 80. To the other end of the shaft 166 is attached an arm, 168, which carries a pin, 169, and a roller, 170, which roller engages in a cam-groove, 171, in the cam 172, which cam is attached to the cam 131, and revolves with it and transmits an oscillating motion to said lifter-plate 164,

proper to hold up and guide the bag-blank into the gripper-rolls described below.

The mechanism for drawing down the partially-folded bag into the diamond shape and 5 delivering it from the first traveling bed to the second traveling bed will now be taken up. This apparatus includes besides a roll or rolls for pressing along the partially-folded blank a 10 sweeper having reciprocating (by which term we include "rotary reciprocating") fingers operated simultaneously in opposite directions during the stroke of the sweeper. Said sweeper may be greatly modified as to its structure within the scope of our invention, and it is 15 shown in two forms, of which the preferred form is incorporated in the principal views of the machine. Instead of the two gripper-rolls one roll having thereon gripper-fingers may be employed to pass along the bag-blank to 20 the second folding-bed, or the said blank may be delivered directly to this latter bed, as shown in our United States Patent No. 331,722, dated December 1, 1885.

Arranged in front of the rocking carriage 25 are shown two upper gripping-rolls, 175 and 176, (see Figs. 24 to 26,) placed above two lower gripping-rolls, 177 and 178, and in front of these gripping-rolls is shown the cylinder 180, above which are represented pasting devices, and in front of which are shown flap-folding devices, all to be hereinafter explained.

The cylinder 180 is fixed to a shaft, 181, which revolves in uprights 182 and 183, attached to the bed 20 of the machine. To this shaft 181 a gear, 184, is attached, which is driven from the intermediate gear, 185, which meshes into the gear 193, fastened to the shaft 89 in the bracket 90. The gear 184 also meshes 30 into an intermediate gear, 186, which drives a gear, 187, upon the shaft 188, upon which the lower gripper-rolls, 177 and 178, are attached. The shaft 188 runs in adjustable boxes 189 and 190, placed in grooves in the uprights 182 and 183. These boxes are supported by spiral springs 191 and 192 in the uprights 182 and 183. To the other end of the shaft 188 is attached another gear, 194, and meshing 35 into the two gears 194 and 187 are shown two small gears, 195 and 196, fastened to shafts 197 and 198, which run in brackets 199 and 200, and carry the two upper gripper-rolls, 175 and 176, the brackets 199 and 200 being fastened to the uprights 182 and 183. By this 40 arrangement of the shaft 188 in boxes 189 and 190, together with the spiral springs 191 and 192, the lower gripper-rolls, 177 and 178, are pressed upward against the upper gripper-rolls, 175 and 176. Attached to the upper 45 ends of the brackets 199 and 200 is shown a rod, 203, upon which a sector-lever, 204, oscillates, one of whose ends terminates in an arm, 205, carrying two sweeper-shafts, 206 and 207, whose lower ends are bent at about right angles to form the sweeper-fingers 206' and 207', and to whose upper ends are fastened sector-pinnions 208 and 209, respectively. The sector-

pinion 208 has an arm upon which a stud, 210, is fixed, upon which a roll, 211, is shown, engaging in a cam-groove, 212, of the cam 213, 70 fixed on rod 203. As the arm 205 is oscillated the sweeper-shafts 206 and 207 receive a rotary reciprocating motion, being vibrated by means of the roller 211, working in the cam 213. The arm 205 also carries a plate, 214, 75 (see Fig. 26,) whose functions will be herein-after described. The arm 205 derives its oscillating motion from the sector 204, meshing into a sector-lever, 215, carried on the stud 216, fastened to the upright 183. The other 80 end of the lever 215 carries a stud, 217, and a roll, 218, engaging in the cam-groove 219 of a cam, 220, on shaft 221, which shaft runs in the upright 183, and is driven by a gear, 222, meshing into the gear 223 on shaft 224, the latter 85 gear meshing into the gear 184, as before described.

A plate, 226, is shown in Figs. 24 to 26, fastened to an arm, 227, and having a vibratory motion with it upon a hub, 228, of the bracket 90 200. At the other end of the arm 227 is shown a sector-gear, 229, meshing into a sector-arm, 230, fastened to a shaft, 231, in the upright 183. To the other end of the shaft 231 is fastened the arm 232, carrying the stud 233, and 95 the roller 234, engaging in the cam-groove 235 of a cam, 236, and fastened to the shaft 188. This cam 236 communicates the proper vibrating motion to the plate 226. The plate 226 has two extensions reaching to both sides of 100 the upper gripper-rolls, 175 and 176, and over the lower gripper-rolls, 177 and 178. Between these upper two rolls, and extending beyond them, are shown two guides or fingers, 237 and 238, which are secured to a rod, 239, fixed in 105 the uprights 182 and 183.

We will now describe the operation of the various mechanisms connected with the second traveling folding-bed as we prefer to construct them. They comprise paste-applying devices, 110 creasing and gripping apparatus, and flap-folding devices operating to retract the bag upon the traveling folding-bed, which devices form an important feature in our invention.

Above the cylinder 180, and upon the shaft 115 224, the paster-roll 242 is so placed as just to clear the cylinder 180. The roll 242 has an extension, 243, forming two paste-applying surfaces, which lengthen the central paste-applying surfaces of the roll 242. Paste is applied to these surfaces by a paste-sector, 244, fastened to the shaft 221, which receives paste from a distributing-roll, 245, upon the shaft 246, which runs in the upright 183, and is 120 driven by a gear, 247, meshing into the gear 222. Paste is taken from a paste dish, 248, supported by a rod, 249, fastened to the upright 183. The paster-roll 242 carries two creasing-blades, 251 and 252, which are as wide as the cylinder 180. The paster-roll 242 125 also carries two pressers or sector-rolls, 255 and 256, the diameter of which is a little larger than that of the roll 242, being just half the diameter (or other aliquot part) of the cyl-

inder 180, and when over this cylinder just touching it.

The cylinder 180, owing to its double size, as stated, is provided with duplicate sets of gripping, creasing, and folding devices, which devices are arranged diametrically opposite one another. For simplicity and greater clearness, we will describe one set of each device, it being understood that the description of the parts and operation of one set will apply equally to those of the other.

The grooves 257 and 258 match the creasing-blades 251 and 252 upon the roll 242, which blades enter the grooves a short distance as the cylinder revolves. A little beyond the first creaser-groove in the cylinder 180 is arranged a pair of yieldingly-held grippers, 259 and 260, which are secured to a shaft, 261, that oscillates in bearings in the cylinder 180. Said grippers 259 and 260 project through holes in the rim of the cylinder 180, and are bent so as to reach over and press upon the outer circumference of this cylinder. This pressing is effected by a small spring, 262, which rests upon the arm 263, attached to the shaft 261 at its outer end. The grippers 259 and 260 are raised and lowered at suitable intervals by means of the roller 265 upon the arm 263 coming in contact with the cams 266 and 267. These cams are secured to a hub, 268, which is an extension of the upright 182, and through whose center the shaft 181 revolves.

In the cylinder 180, and to the rear of the second creaser-groove, 258, there is placed in the cylinder a shaft, 270, extending through the cylinder and carrying on both sides thereof a pair of take-up arms or retracting-fingers, 271 and 272, whose outer ends are bent at right angles and extend into recesses 273 and 274 in the cylinder 180. In Fig. 24 one of these arms, 272, is omitted for greater clearness, the shaft 270 being broken off a little beyond the edge of the cylinder. These ends of the arms 271 and 272 are represented inside the circumference of the cylinder 180, and are moved outward beyond its circumference at proper intervals by means of an arm, 275, fastened to the shaft 270. This arm carries a stud, 276, and a roll, 277, running in a cam-groove, 278, of a cam, 279, shown clearly in Fig. 25, where the web 281 of the cylinder 180 is shown broken away. The cam 279 is omitted in Fig. 24 for greater clearness, but is shown in Figs. 25, 27, 30, and 31, being secured to a hub, 282, which forms an extension of the upright 183. As the cylinder 180 revolves the cam 279 transmits motion to the take-up arms 271 and 272, giving them a vibratory motion at proper intervals.

The cylinder 180 also carries at its sides a pair of side clips, 285 and 286, which are shown in Figs. 25, 27, 30, and 31, and only on one side of the cylinder in Fig. 24, being omitted on the other side for greater clearness. These side clips, 285 and 286, are placed at an angle on the sides of the cylinder and oscillate upon

studs 287 and 288, which are secured to ears 289 and 290, attached to the cylinder 180. The outer ends of the side clips, 285 and 286, are bent inward toward the cylinder, and each of the clips has two projections, the shorter ones being represented by the numbers 291 and 292, which projections extend a little in advance of the second creaser-groove, 258, and when closed over the cylinder 180 reach over its edge a short distance. The longer projections, 293 and 294, extend farther inward and form guiding-fingers, which, when swung over upon the cylinder 180, reach a little to the rear of the second creaser-groove, 258, and considerably inward from the edge of the cylinder. These projections 293 and 294 are beveled backward, being open at the front, and being closed at the back by corner-pieces 295, reaching to within a short distance of the surface of the cylinder, as shown clearly in Figs. 30 and 31. These clips 285 and 286 receive an oscillating motion at their inner end by means of studs 296 and 297 and rollers 298 and 299, which engage in cam-grooves 300 and 301 in cams 302 and 303, which cams are fixed to the hubs 268 and 282 of the uprights 182 and 183. Cam 303 is omitted in Fig. 24 for greater clearness of illustration. These cams 302 and 303 are constructed to communicate the required oscillating motion to the side clips, 285 and 286, at proper intervals during the revolution of the cylinder 180.

Operating in connection with the second traveling folding-bed are shown flap folding and delivering apparatus, which operate to do the final flap-folding and to deliver the bags from the machine.

Arranged in front of the cylinder 180 upon the shaft 310, which shaft rests in bearings in the two uprights 308 and 309 on the bed 20 of the machine, are shown three folder-arms, an inner one, 311, and two outer ones, 312 and 313, all of whose ends are bent and terminate in blades 314, 315, and 316, respectively. These blades receive an oscillating motion by means of a sector, 317, fastened to the shaft 310, which meshes into a sector-ended lever, 318, which oscillates upon a stud, 319, fixed to the upright 309. At the other end of the lever 318 is shown a stud, 320, and a roller, 321, which engages in the cam-groove 322 of a cam, 323. This cam 323 is fixed to a shaft, 324, which turns in the uprights 308 and 309, and is driven by a gear, 325, meshing into a pinion, 326, which is driven by a shaft, 327, running in the upright 183, by means of a gear, 328, meshing in the gear 184, before described. The shaft 324 carries a roll, 329, above which is shown another roll, 330, upon a shaft, 331, running in the uprights 308 and 309. The shaft 331 is driven by a gear, 332, meshing into the gear 325, before described. The rolls 329 and 330 are arranged so as just to clear one another. Between the cylinder 180 and the rolls 329 and 330 are shown two other rolls, 335 and 336, which are narrow, and which are secured to shafts 337 and 338, which run in the uprights 308 and 309. These shafts are driven by gears 339 and 340, respect-

ively, the former meshing into the gear 326 and driven by it.

In front of the cylinder 180 is shown a curved plate, 341, which extends at both sides 5 of the rolls 335. This plate 341 extends a little beyond the sweep of the blades 315 and 316, which blades in their motion downward pass at both sides of the roller 336 and a little beyond it. The roller 336 is placed just to 10 clear the roller 335.

The operation of the machine is as follows: Continuous tucked paper tubing 57, while being manufactured upon a former, 56, by apparatus substantially as shown in our Patent 15 No. 331,722, dated December 1, 1885, is drawn forward into the machine by the drawing-rolls 36 and 37, and passes between the pressing-rolls 53 and 54 and under the lip-knife 60. In its progress forward from the former through 20 these rolls, the tube 57 envelops the former-knife 58, the upper ply, 14, Fig. 3, of the tube passing over the knife 58, while the lower ply of the bag and the two plies of the tucks pass below it. At the same time the slitter-knives 25 rotate and cut slits 4 and 5 into the tube, doing this once for each bag-length required. The tube is fed forward from the knife 58 onto the upper portion of the first traveling folding bed or carriage, 80, during its backward 30 stroke, while the presser-plate 98 is elevated to its upper position, as shown in Fig. 18. The presser-plate 98 descends upon the tube and clamps it to the carriage 80 at approximately the time when the latter commences its 35 forward stroke, a sufficient amount of this tube being fed beyond the forward end of this presser-plate to form a bag-bottom. The forward motion of the carriage being at this point slower than that of the tube 57, the tube is bent 40 downward, as shown in Fig. 15, forming a slackness therein, until the striker 61 passes in front of the knives 58 and 60 and takes up this slack and breaks or tears off a bag-length, all of which is done once for every revolution 45 of the crank and every stroke of the carriage. The taking up of the slack by the striker 61 in this manner causes the paper to stand at an angle approaching ninety degrees to the cutting-edges of the two knives, so that as the striker 50 passes them it tears off the tube with great ease and produces a clean break. The position of the parts at the beginning of the breaking is shown in Fig. 18. The shape of the cut produced is shown in Figs. 1 and 2 by the lip 6 55 in the end of the bag and the recess 7 in the oncoming tube. The breaking off is so timed as to bring the slits 4 and 5 at the forward end of the broken-off tube 57.

During the backward stroke of the carriage 50, and while the tube passes under the presser-plate 98, the tuck-blades 132 and 133 and the box-blades 136 and 137 are rocked forward into the tucks 2 and 3 of the paper tube, as shown in Figs. 15, 16, and 19. These blades 65 are enabled to enter the tucks of the tube on the backward stroke of the carriage 80, because the upper and lower plies of the tucks

of the blank spring apart. This springing apart occurs because the drawing rolls 36 and 37, before described, have not flattened the bottoms of the inwardly-projecting tucks 2 and 3, nor the edges of the blank, thus leaving the tucks elastic and self-opening. The entering of the blades on the backward stroke of the carriage has the important advantage of gaining time for making the primary fold, which is thereby readily completed before the carriage finishes its forward stroke. By this means the machine has a much greater capacity with less velocity of movement in many of its parts. After these blades have entered, and after the presser-plate 98 has gripped the tube, and during the forward motion of the carriage, the box-blades 136 and 137 are turned over backward, thus folding the forward part 80 of the bag, as shown in Fig. 21. During the forward motion of the carriage the sweeper-shafts 206 and 207 and the plate 214 enter the forward end of the box 8, and after the box has been folded, as shown in Fig. 21, they 85 swing forward and draw the box 8 down into the diamond shape 9, as shown in Figs. 22, 24, and 25, the bent feet of the sweeper-shafts being turned outward, as shown in Figs. 24 and 28. During this operation of forming the diamond the lifter-plate 164 is brought upward, pressing the forward end of the diamond 9 against the plate 214, thus holding it securely. At the same time the plate 226 descends upon the flattened diamond and prevents it from 90 springing upward as the bag passes forward. The sweeper-shafts 206 and 207 then draw the diamond forward into the bite of the gripping-rolls 175 and 177 and 176 and 178. The presser-plate 98 is then elevated a little, the lifter-plate 105 is dropped a little, and the tuck-levers 122 and 123, carrying the four blades, withdraw from the bag, taking the position shown in Fig. 20, after which the box-blades revolve back to the position shown in Figs. 15 and 19. The 110 sweeper-shafts 206 and 207 are then driven forward with greater speed than that of the bag, and the bent ends 206' and 207' thereof are turned inward and withdrawn from the bag, as shown in Fig. 29. As the bag passes 115 forward it is flattened by passing under the rolls 175 and 176 and plate 226 and over the rolls 177 and 178, the rearward half of the diamond being fully flattened between the plate 226 and the plate 98. It then passes forward 120 under the fingers 237 and 238 and upon the cylinder 180, the forward end of the diamond being gripped by one of the pairs of grippers 259 and 260, which draws the bag forward 125 under the paster-roll 242, which applies the paste to the diamond. The creaser-blade 251 enters the recess 257 in the cylinder 180 and creases the bag across the line *o p*, Figs. 10 and 12, to facilitate subsequent folding operations. The creaser-blade 252 then enters the 130 groove 258 in the cylinder 180 and creases the bag across the line *q r*, Fig. 10. This causes the second flap, 11, to rise into the position shown in Figs. 11, 25, and 27. While

in this position, one of the two pairs of side clips, 285 and 286, is rocked upon the cylinder and over the edge of the bag, the projections 291 and 292 taking a position over the 5 edges of the bag and preventing the bag from rising from the cylinder. This motion of the side clips also projects the ends 293 and 294 over the bag and behind the flap 11, which has been raised, as before described. As the 10 cylinder revolves forward the flap 11 is supported by the projections 293 and 294, which prevent it from dropping down to its former position. After the flap 11 has passed beyond the roll 242 the presser-sectors 255 and 256 arrive upon the rear end, 1, of the bag and firmly press it to the cylinder 180 as this revolves, as 15 shown in Figs. 30 and 31. By this time the grippers 259 and 260 will have released the forward end of the diamond, which will spring 20 outward under the folding-blades 315 and 316 and over the plate 341 and over the roll 336, as shown in Fig. 30. While the presser-sectors 255 and 256 pinch the rear end of the bag the forward ends or fingers of the take-up arms 25 271 and 272 move outward beyond the circumference of the cylinder to the position shown in Fig. 30, and from that to that shown in Fig. 31. This draws the forward end of the bag backward upon the cylinder, the projections 30 on the side clips, 285 and 286, allowing the bag to do so. The object of pulling the bag backward is to fold forward the second flap, 11, as shown in Figs. 30 and 31. This is accomplished by the upper ends of the projections 35 293 and 294 of the side clips coming in contact with the flap 11 above *q r*. The bag is drawn backward until it comes in contact with the corner-pieces 295, after which the take-up arms 271 and 272 are gradually 40 turned. The flap 11, having been folded forward, is now assisted by the folding-blade 314, as shown in Fig. 31, which moves downward with the folder-blades 315 and 316, the first one serving to keep the flap 11 close to the 45 bag-bottom, while the last two double over the first flap, 10, at the folding-line *o p*, folding it upon the flap 11 and delivering the bag between the rolls 335 and 336. The side clips, 285 and 286, are meanwhile rocked outward 50 from the cylinder, thus freeing the folded bag, which then passes between the rolls 329 and 330, which flatten and deliver it completed. The bag then passes to suitable drying apparatus. (Not shown.)

55 In order to pass the bag between the gripping-rolls 175 and 176 and 177 and 178, the bearings supporting the latter rolls are made elastic, as represented. This same arrangement of elastic bearings may be applied to the 60 rolls 242, 336, and 330, in order to avoid crushing the bag to too great an extent; but such bearings are not shown in the drawings.

The drawings represent double sets of grippers, 259 and 260, and of side clips, 285 and 65 286, and of take-up arms 271 and 272, each of which sets acts in succession upon the partially-folded bags as they are delivered to the cylinder.

der. This duplication of parts, though not essential, is believed to be preferable on account of the enlargement of the cylinder thereby obtained, which allows the use of larger cams at the side of the cylinder, and also does not require the bag to be bent around too small a circumference. 70

We will now describe some modifications of 75 mechanisms that may be applied to the first traveling folding-bed without departing from the spirit and scope of our invention. The first of these is shown in Figs. 32 and 33, and represents a modified form of mechanism for 80 imparting motion to the presser-plate 98. The traveling folding-bed is shown, as before, at 80, pivoted on the shaft 81, between the two cams 130 and 131, in which the presser-plate shaft 104 is also shown, and upon which shaft the 85 presser-arms 102 and 103 are fixed, at whose extremities are swung brackets 100 and 101 on the pivots 105 and 106, the lower end of the bracket 100 being steadied by the link 107, swinging upon the pivot 108, projecting from 90 the carriage 80, and to which brackets the presser-plate 98 is fastened, all in the same manner as before described. The proper motion is imparted to this presser-plate 98 by mechanism driven from a cam upon the shaft 95 81. The cam-groove is shown at 350, cut in the side of the cam 130. A roller, 351, upon the stud 352 engages in the groove, the stud being secured to the lower end of a lever, 353, which swings upon a stud, 354, fastened to an ear, 100 355, upon the carriage 80. To the other end of the lever 353 a connecting-rod, 356, is jointed upon a stud, 357. This connecting-rod at its other end is jointed upon a stud, 358, to the arm 359, which arm is fastened to the shaft 104, before described. Motion is imparted to the presser-plate 98 by means of the shaft 104, being driven by the arm 359, the connecting-rod 356, the lever 353, and the cam-groove 350, which groove is cut to impart this motion 105 110 at proper intervals.

A second modification is applied to the first traveling folding-bed, and is shown in side view in Fig. 34 upon a reduced scale. Here the carriage 80 is not swung upon the central 115 shaft, 81, but is swung upon a pivot, 365, adjacent thereto, which pivot is fastened to a bracket, 366, upon the bed 20 of the machine. The shaft 81 carries the cam 130. The carriage 80 carries mechanisms similar to that described in Fig. 32.

It is obvious that all motions communicated by cams upon the shaft 81 to mechanisms upon the carriage 80 will have to be so far modified as to allow for the different position 125 of the pivot 365; but these differences of motion do not effect the results obtained in the folding operations performed upon the bag-blank.

We will next proceed to describe various 130 modifications that may be applied to the second traveling folding bed and refer to the mechanism for retracting the bag upon the bed, as well as to the bed itself. In the principal fig-

ures this bag-retracting apparatus is shown as constructed in Figs. 24, 25, 26, 27, 30, and 31, and here the retracting-fingers are arranged to act from the inside toward the outside of 5 the endless folding-bed 180.

A modified form of retracting-fingers, operating from the inside to the outside of the folding-bed, is shown in Figs. 35 and 36. Here in place of the swinging take-up arms there 10 are shown two radially-sliding retracting-fingers, 370 and 371. These fingers slide in grooves 372 and 373 in the cylinder 180, and receive a reciprocating motion by means of sectors 374 and 375, meshing into racks cut 15 upon the fingers 370 and 371. The sectors 374 and 375 are pivoted upon the shaft 376, to whose outer end an arm, 377, is fastened, which carries upon its extremity a stud, 378, and roller 379. This roller engages in a cam-groove, 380, in a cam, 381, which is fixed to the hub 282 of the bracket 183. The remaining parts shown in Fig. 35—that is, the paster-roll 242, the creasing-blades 251 and 252, and the presser sector-roll 255 on the shaft 224—are 20 similar to the parts before described, as are 25 also the side clip, 285, the stud 287, roller 298, and the cam 302.

The operation of the retracting-fingers 370 and 371 is similar in all respects as to time of 30 movements to the retracting-fingers 271 and 272, and they perform the same functions.

We will now describe a modified form of a traveling folding-bed, which carries a bag-retracting mechanism operating outwardly to retract the bag. This is shown in side view in 35 Fig. 37, wherein the traveling folding-bed is represented as a carriage, 390, upon a slide-way, 391, upon which it may receive a reciprocating motion from a connecting-rod, 392, 40 connected to a pin, 393. This carriage 390 moves backward and forward once to each revolution of the paster-roll 242 and presser sector-roll 255 upon the shaft 224. The roll 242 carries the creasing-blades 251 and 252, 45 which enter the creasing-grooves 394 and 395 in the carriage 390 in succession as the carriage passes beneath the roll 242, and so creases the bag-blank at the folding-lines *o p* and *q r*, Fig. 16. The carriage 390 carries at its sides 50 a pair of side clips, 396, one of which only is shown in the drawings. This clip 396 is pivoted to the stud 397, fastened to an ear, 398, of the carriage 390. The pair of clips 396 are provided with a pair of studs, 399, upon which 55 rollers 400 revolve, which engage in right and left hand spiral cam-grooves in a pair of cams, 401, fastened to a shaft, 402. As the shaft is oscillated the pair of cams 401, by means of their spiral grooves, impart a swinging motion to the pair of side clips, 396, precisely in 60 the same manner as described in our United States Patent No. 331,722, dated December 1, 1885, and clearly shown in Figs. 28 and 29. The pair of clips 396 have projections 291 and 65 293 and corner-pieces 295, similar to those before described. The oscillating motion is imparted to the shaft 402 by means of a lever,

403, whose upper end comes in contact with a rod, 404, and whose lower end comes in contact with a spring-pawl, 405, as it reciprocates. 70 The carriage 390 also carries a pair of retracting-fingers, 406, fastened to a shaft, 407, to which shaft an arm, 408, is secured, carrying a roller, 409, which is vibrated as the carriage reciprocates by means of a switch-cam, 410, 75 which is hinged to a stud, 411, upon a track, 412. The roller 409, coming in contact with the switch-cam 410 in the forward motion of the carriage 390, moves the retracting-fingers 406 outwardly, as shown in the drawings, and 80 after the roller 409 has passed the end 413 of the switch-cam 410 it drops down upon the track 412, and passes, on the backward stroke of the carriage, beneath the switch-cam 410, elevating it until it has passed beyond its 85 length. The successive operations of bag-retracting and flap-folding are similar in this traveling folding-bed to the endless one described—that is, after the bag has been creased and the pair of side clips, 396, have been 90 swung over the bag and the presser sector-roll 355 has gripped the tail of the bag upon the carriage 390 the retracting-fingers 406 are operated outwardly as the carriage 390 advances, thus drawing the forward part of the bag back, 95 drawing the flap 11 underneath the projections 293 of the clips 396, after which the retracting-fingers drop, and the next folding operations may be performed.

The next two modifications of retracting-fingers operating in connection with an endless traveling folding-bed are shown in Figs. 38 to 41. In these modifications the retracting-finger operates from the outside of the bed, pressing the bag inwardly into it. The first 100 of these modifications is shown in two positions in Figs. 38 and 39 in side view, and resembles in all parts Figs. 30 and 31, except that the retracting-fingers and their connecting mechanism are entirely omitted from the cylinder 180. In the place thereof a revolving 105 retracting-finger, 416, is introduced into the combination. This finger 416 is attached to a shaft, 417, which shaft revolves in bearings in the uprights of the machine, and which is 110 driven by a gear, 418, meshing into a gear (not shown) which drives the cylinder 180 and the shaft 181. The outer end of the finger 416 projects in its revolution into a recess, 419, of the cylinder 180, and operates to draw the bag back 115 in the following manner: The partially-folded bag having been gripped upon the cylinder 180, properly creased, as before described, and moved along sufficiently far to enable the presser sector-rolls 255 to grip the bag upon 120 the cylinder, the outer end of the revolving retracting-finger 416 presses upon the bag-blank, forcing it into the recess 419 of the cylinder 180, as shown first in Fig. 38 and then in Fig. 39, drawing the forward end of the 125 bag backward and folding the flap 11 over in a manner similar to that described in the principal figures. During the further revolution of the finger 416 it moves out and away from

the cylinder, operating at its next revolution upon the next bag-blank.

The second modification of the retracting-finger, operating inwardly toward the traveling bed, is shown in Figs. 40 and 41, where, in the place of a revolving retracting-finger, 416, a retracting-finger having a variable motion is shown, traveling in the path shown by the dotted line 422. This finger 423 extends 10 across the cylinder 180 and is attached to a slide, 424, which moves in grooves in a yoke, 425, which is pivoted at 426 to a rocking arm, 427, rocking upon a pivot, 428, attached to the upright 429. At the other extremity of 15 the yoke 425 is shown a crank-pin, 430, fastened to the cam-disk 431, which communicates a rocking motion to the yoke 425. The cam-disk 431 is attached to a shaft, 432, and receives motion through a gear, 433, which 20 meshes into a driving-gear (not shown) upon the shaft 181. Around the crank-pin 430 a cam-groove, 434, is cut, in which a pin, 435, attached to the slide 424, engages. As the cam-disk 431 revolves, imparting a rocking 25 motion to the yoke 425, the slide 424 also receives a reciprocating motion at proper intervals, giving to the finger 423 a motion substantially as that shown by the dotted line 422. The cylinder 180 is provided with the recess 30 419, to allow of the passage of the finger, enabling this finger to retract bag-blanks substantially in the same manner as shown in Figs. 38 and 39.

The next two methods for retracting a bag-blank upon an endless traveling bed are shown 35 in Figs. 42 to 46. The first of these is shown in two positions in Figs. 42 and 43. In these views the points of similarity to the methods described in the principal figures consist of 40 the cylinder 180, the side clips, 285, (which are here only partially shown,) the pasteur-roll 242, and the creasing-blades 251 and 252. Instead of retracting the bag by means of fingers, previously described, it is pulled back bodily 45 sufficiently to fold forward the flap 11 by means of gripping-fingers 438 and 439, which grip the bag and hold it long enough to effect the desired retraction. The fingers 439 are pivoted on the hub 448 of the cylinder, 50 and the fingers 438 are pivoted on the shaft 224. During the forward motion of the cylinder 180 a retarded motion is communicated to the fingers 439, which communicate a retarded motion to the fingers 438, opening the 55 spring 440, as shown in Fig. 43. The retarding motion communicated to the fingers 439 is effected in the following manner: To the fingers 439 are attached sectors 441, meshing into sectors 442 upon a shaft, 443, in the cylinder 60 180. To this shaft is fixed an arm, 444, carrying a roller, 445, engaging in a cam-groove, 446, in the cam 447. As the cylinder 180 revolves the roller 445 is moved outwardly by the cam-groove 446, imparting, through the 65 lever 444, shaft 443, and sectors 442 and 441, a retarding motion to the fingers 439. The same object may be attained by stopping the motion

of the fingers 449, as may be desired. After the bag has been retracted the grippers 438 and 439 both move forward into their positions 70 of rest, as shown in Fig. 42.

The second method shown in Figs. 44 to 46 performs precisely the same bodily retraction of the bag as that just described, the only point of difference being in the method of 75 gripping the bag itself. Here the retracting-fingers 450 and 451, carried by the cylinder, are pivoted on a shaft, 452, in the cylinder 180, and receive a retracting motion by means of an arm, 453, carrying a roller, 454, engaging in a cam-groove, 455, of the cam 456, fastened to the hub 282 of the bracket 184. The upper ends of the retracting-fingers 450 and 451 are provided with upper retracting-fingers, 457 and 458, fastened to a shaft, 459, which 80 shaft oscillates in these fingers 450 and 451, being vibrated by an arm, 460. (Shown in an enlarged view in Fig. 47.) This arm 460 is rocked in and out by posts 461 and 462, (shown in section in the drawings,) they being fixed 85 to the main bracket of the machine. To the shaft 459 is secured a small cam, 463, against which a bolt, 464, is pressed by means of a spring, 465, which bolt and spring are held by a projection upon the finger 450. This construction of a pressing-bolt operating in connection with fingers is similar to that shown in Figs. 28 and 29 of our United States Patent No. 331,722, dated December 1, 1885. In this combination of parts the end of the bag-blank 90 419 is gripped between the retracting-fingers 450 and 451 and the upper fingers, 457 and 458, as shown in Fig. 44. A retarding motion is then given to these fingers, drawing the bag-blank into the position shown in Fig. 45. 105

We will next proceed to describe a modification of the mechanism for operating the fingers upon the sweeper for drawing down the partially-folded bag into the diamond shape. This is shown in Figs. 48 and 49. 110 Here the rod 203 supports the cam 213 and sector-lever 204, with its arm 205, all similar to those shown in the principal figures. In Figs. 48 and 49 the fingers are constructed at their lower ends substantially as shown in the 115 principal figures, and are arranged and operated as follows: Two fingers, 468 and 469, are pivoted at 470 and 471 on the arm 205 of the lever 204, and are provided with sectors at their upper ends, which mesh into one another. The finger 468 is made in the shape of a lever, whose upper end carries a roller, 472, engaging in the cam-groove of the cam 213. As the arm 205 vibrates, as described in the 120 principal figures, the lever-finger 468 communicating motion to the finger 469 at proper intervals through the cam 213, the fingers are swung together and may be drawn from the forward end of the diamond.

These various alternate devices will form 130 the subject-matter of future applications for patents, and therefore have only been broadly described in order to point out similarity in the object accomplished.

We disclaim the specific form of retracting apparatus shown in Figs. 35 and 36 and that shown in Fig. 37, because those forms were invented by Edward E. Claussen; and we disclaim the specific form of retracting apparatus shown in Figs. 42 and 43, because it was invented by William H. Honiss alone; and we disclaim herein the specific form of retracting apparatus shown in Figs. 38 and 39 and that shown in Figs. 40 and 41 and that shown in Figs. 44, 45, 46, and 47, because we will claim those in separate applications for Letters Patent of the United States; nor do we herein claim the mechanical motions which we describe as working the blades 132 and 136 upon the top of the rocking carriage 80, for those motions are applicable to the performance of a variety of functions upon rocking carriages in a variety of machinery, and will be made the subject of a separate application by us for a patent of the United States.

Having thus described our invention, we claim—

1. The combination of drawing rolls to bring the tubing into the machine, a carriage provided with a clamping apparatus to seize and hold that tubing, and two knives and a striker between those rolls and that carriage operating to sever the tubing when the rolls and the carriage have clamped it and have made a slack therein, all substantially as described.

2. The combination, in a bag-machine, of the folding-bed thereof, two oppositely-disposed levers, each carrying a pair of blades, substantially as described, the cams 130 and 131, working those levers, and the cam 155 and connecting mechanism, substantially as described, working one member of each pair of those blades, all substantially as described.

3. The combination of the rocking carriage 80, the levers 122 and 123, pivoted to that carriage and provided with the blades 136 and 137, respectively, the cams 130 and 131, working those levers, and the cam 155 and connecting mechanism, substantially as described, working those blades, all substantially as described.

4. The combination of the rocking carriage 80, the presser-plate 98, rising and lowering upon that carriage, the cam 130, and mechanism, substantially as described, between that cam and that presser-plate and operating to work the latter, all substantially as shown in Figs. 32, 33, and 34 of the accompanying drawings, and described in the foregoing specification.

5. The combination of the rocking carriage 80, the lifter-plate 164, pivoted to that carriage and projecting forward therefrom, the cam 172, and mechanism, substantially as described, between that cam and that lifter-plate and operating to work the latter, all substantially as described.

6. The combination of a reciprocating carriage carrying a clamping apparatus, the plate 214, oscillating forward on the arc of a circle, and the lifting-plate 164, the working end of

which moves forward on a curved line corresponding with that arc, so as to clasp the forward end of the diamond between those two plates and to deliver the same to mechanism adapted to receive it, all substantially as described.

7. The combination of two mated bent sweeper-fingers reciprocating toward and from each other crosswise of the bag-blank, and reciprocating side by side lengthwise of the bag-blank, all substantially as described.

8. The combination of the two axially-oscillating sweeper-shafts 206 and 207, provided with the terminal sweeper-fingers 206' and 207', respectively, and worked together by means of the sector-pinions 208 and 209 while oscillating side by side, all substantially as described.

9. The combination of a reciprocating sweeper-arm carrying oppositely-disposed reciprocating sweeper-fingers and a cam operatively connected with those fingers for working them during the stroke of the sweeper-arm, all substantially as described.

10. The combination of the oscillating arm 205, the shafts 206 and 207, carried on that arm and having bent sweeper-fingers at the ends thereof, and a cam operatively connected with those shafts and imparting thereto simultaneous movements in opposite directions, all substantially as described.

11. The combination of lower and upper gripper-rolls, the latter being divided by a clear space in the middle, and a reciprocating sweeper having its stroke extending into that space and operating to draw the forward end of the diamond into the bite of the upper and lower rolls, all substantially as described.

12. The combination of lower and upper gripper-rolls, the latter being divided by a clear space in the middle, the plate 164 under the diamond, and the plate 214 over the diamond, both plates operating to clasp the forward extremity of the diamond and to carry it into that clear space, so as to deliver the diamond to the bite of the lower and upper gripper-rolls, all substantially as described.

13. The combination, in a bag-machine, and with the folding-bed thereof, of side clips rearward of the second flap, a presser or pressers operating on the bed rearward of the side clips to clamp to the bed the rearward end of the bag-blank, and a retracting finger or fingers operating laterally against the bag-blank between said presser and clips, whereby the forward end of said blank is drawn back under said clips for the folding over of the second flap, substantially as described.

14. The combination, in a bag-machine, and with the traveling folding-bed thereof, of side clips carried with said bed rearward of the second flap, a presser or pressers operating on the bed rearward of the side clips to clamp to the bed the rearward end of the bag-blank, and a retracting finger or fingers carried on the bed and operating laterally against the bag-blank between said presser and clips,

whereby the forward end of said blank is drawn back under said clips for the folding over of the second flap, substantially as described.

5 15. The combination, in a bag-machine, and with the cylindrical traveling folding-bed thereof, of the side clips rearward of the second flap of the bag-blank, a presser operating to clamp said blank rearward of said clips, and a retracting finger or fingers operating outwardly against the blank between said clips and said presser, whereby said blank is drawn back under the clips for the folding of the second flap thereof, substantially as described.

10 16. The combination, with the revolving cylinder 180 and with the presser acting against said cylinder, of the side clips, 285 286, the retractor pivoted to the cylinder, and cams and connections actuating said clips and retractor, all constructed and operating substantially as described.

15 17. The combination of cylinder 180, having groove 258, creasing-blade operating in said groove, and clips 285 286, carried on the cylinder and each having one finger forward and one rearward of said groove, all constructed and operating substantially as described.

18. The combination, in a bag-machine, of the traveling folding-bed having grooves cross-wise to the motion thereof, mechanism holding the bag-blank on said bed over said grooves, creasers operating in connection with the grooves to crease the blank, rolls for receiving the creased blank from said bed, and the blades operating to deliver the blank folded at said creases from said bed to said rolls, all substantially as described.

30 19. The combination, in a bag-machine, of the traveling folding-bed carrying the partially folded and creased bag-blank, rolls 335 336, the lower blades, 315 and 316, and blade 314 above and between said lower blades, all arranged and operating substantially as described.
